UNITED STATES PATENT OFFICE.

GEORGE WARNER, OF DEARBORN, MONTANA.

GATE-LATCH.

No. 809,544.

Specification of Letters Patent.

Patented Jan. 9, 1906.

Application filed March 25, 1899. Renewed June 19, 1905. Serial No. 266,043.

To all whom it may concern:

Be it known that I, GEORGE WARNER, a citizen of the United States, and a resident of Dearborn, Lewis and Clarke county, Montana, have invented certain new and useful Improvements in Gate-Latches, of which the following is a specification.

The present invention relates to a latch mechanism more especially adapted to gates or doors which open in either direction.

The object of the present improvement is to provide a simple and effective latch mechanism with which either a rebounding of the gate from its proper closure position or the swinging of such gate past such proper closure position is prevented in a ready and effectual manner and which involves an automatic means, which is operatively connected with the main latch mechanism for effecting the initial stoppage and holding of the gate at such proper closure position previous to the engagement of the latch mechanism to secure the gate in such closure position, all as will hereinafter more fully appear and be more particularly set forth in the claims. I attain such objects by the construction and arrangement of parts illustrated in the accompanying drawings, in which—

Figure 1 is a fragmentary elevation of a swinging gate to which the present latch mechanism is applied; Fig. 2, a front elevation of the present improved latch with the front cover removed to illustrate the interior latch mechanism and with the latch-bar in section; Fig. 3, a vertical section of the same on line 3 3, Fig. 2. Fig. 4 is a view similar to Fig. 2, illustrating the parts in the position they would take as the latch-bar moves out upon an opening movement of the gate; Fig. 5, a similar view illustrating the parts in the position they would take just at the time when the latch-bar in a closure movement of the gate swings into position ready to drop into the central locking-recess of the latch; Fig. 6, a fragmentary horizontal section taken on a line intersecting the pivot-axis of the triggers 16.

Similar numerals of reference indicate like parts in the several views.

Referring to the drawings, 1 represents the frame or casing of the present latch mechanism, provided at its lower end with counterpart inclined guideways 2 at opposite sides of the central latch-receiving recess 4, such guideways being adapted to act as inclining planes in raising the free end of the latch-bar

3 as the gate or door swings into its closure position. The latch-bar 3 may be arranged in any usual manner, so that it will be capable of a limited rising and falling movement 60 in the operation of latching and unlatching the gate, and while I have shown in Fig. 1 a hand-lever 24 and connecting-link for manually unlatching the bar 3 when the gate is to be opened any other usual provision for manually operating such latch-bar can be used instead when the circumstances so indicate. With a view to cause the latch-bar 3 to ride upon the inclined guides 2 as easily as possible I provide the same upon its bearing- 70 face with a roller 18.

5 5 are two counterpart vertically-movable bolts or bars arranged to slide in suitable guideways within the interior of the hollow chamber which constitutes the upper and 75 latch-mechanism-containing chamber of the main frame 1, such guideways being preferably formed in the upper and lower removable partitions 7 7 for convenience in assembly of the latch mechanism, as well as in 80 subsequent repair or replacement of parts.

8 8 are two counterpart crossed levers having a common and central fulcrum and provided at their lower ends with lifting-studs having individual engagement with the outer 85 turned upper ends of vertical bolts or bars 5 5. At their upper ends the levers 8 8 are formed with cam-slots 9 for operative engagement with connections intermediate of said levers and the latch-bar 3, as hereinafter described.

11 is a vertically-movable rod or bar guided in a vertical guide-recess 12 at the back of the frame 1, its upper end being of a forked or widened form and provided with cam-studs 10, having engagement in the cam-slots 9 of the crossed levers 8, heretofore described. At its lower end the vertical bar 11 is provided with two projecting arms 13, arranged one above the other and spaced apart 100 a sufficient distance to receive between them the latch-bar 3 in order that a vertical movement may be imparted to such vertically-movable bar 11 by the latch-bar as said latch-bar moves vertically into or out of the latch-receiving recess 4.

16 represents two counterpart triggers, which in the construction shown are formed by straight pieces, having when at rest a vertical position with their lower end projecting into the path of the latch-bar, so as to be moved laterally thereby as such latch-bar

swings into place. Such straight trigger pieces are pivoted intermediate of their length to the main casing by means of radius-links 16' and are provided at a point adjacent to their connecting with said links with projections 15, that are adapted to engage in the notches or recesses 14 in the vertically-movable bolts or bars 5 to hold such bolts in their elevated condition. In the present improvement the bolts 5, the levers 8, and triggers 16 will have a symmetrical arrangement at opposite sides of the central vertical line of the latch mechanism, as illustrated in the drawings.

In the construction shown in the drawings the removable partitions 7 rest in sockets 19 in the main frame, and the pivoted levers 8 are provided with counterbalance-weights 20 at their lower ends to counterbalance the weight of the parts connected to the other ends of said levers and an operation of the said levers and their immediately-connected parts by gravity. The front cover portion 21 of the casing that incloses the operating mechanism of the latch is secured in place preferably by long bolts 22, which extend entirely through the posts 23 to hold the entire latch in position.

The operation of my improved latch is as follows: With the gate in a closure position the latch-bar 3 rests within the recess 4 and by means of the lower projection 13 has pulled down the bar 11 and through the instrumentality of the crossed levers 8 and cam slots and studs 9 and 10 has raised the bolts 5 to their elevated position, as shown in Fig. 2, and in which position the projections 15 of the triggers 16 will engage in the notches 14 of said bolts 5 to lock them in such elevated position, such engagement being effected by the force of gravity on the part of the triggers. If now the gate be opened, the latch-bar 3 moving to the right after being first raised vertically out of the latch-recess 4 and moving with it the vertically-movable bar 11 into its elevated position, the above-described parts will assume the position shown in Fig. 4, the lower end of the right-hand one of the triggers 16 being pushed along by the latch-bar 3 until its upper end strikes the upper end of the left-hand trigger, as shown at 17, when the left-hand bolt 5 will be released from its engagement with said left-hand trigger and drops into the position shown in Fig. 4 and in which position it constitutes a stop for the latch-bolt in a subsequent return movement. As the gate is subsequently swung back into a closure position the latch-bar 3 impacts against the left-hand bolt 5 and drops into the latch-recess 4, carrying with it by means of the projections 13 the

vertically-movable bar 11, which serves to raise the left-hand bolt 5 again to its elevated position. (Shown in Fig. 2.) Any tendency of the gate to rebound or swing backwardly after the latch-bar 3 strikes the left-hand bolt 5 is prevented by the disengagement and dropping of the right-hand bolt 5 into position shown in Fig. 5, due to the movement of the right-hand trigger by the latch-bar.

It is obvious that if the present invention be used on a gate which opens in one direction only but one-half of the construction heretofore described will be necessary, and either half can be used, depending upon direction in which the gate opens. It is also obvious that other changes of detail may be made without departing materially from the spirit of the present invention.

Having thus fully described my said invention, what I claim as new, and desire to secure by Letters Patent, is—

1. A gate-latch having a pivoted latch-bar adapted to engage by gravity in its engaging recess, in combination with a vertically-movable stop-bolt, a trigger mechanism for said stop-bolt arranged in the path of the latch-bar and adapted to be operated by the latch-bar in a closing movement of the gate, to release the stop-bolt and allow the same to move downward into a position to prevent a rebound of the gate, substantially as set forth.

2. A gate-latch comprising in combination, a latch-bar, a pair of vertically-movable stop-bolts, locking-triggers for said stop-bolts, a pair of pivoted levers for raising said stop-bolts, and means whereby the movement of the latch-bar operates said triggers, substantially as set forth.

3. A gate-latch comprising in combination, a latch-bar, a central recess in the latch-frame for receiving said bar, a vertically-movable stop-bolt, a locking-trigger for said stop-bolt, and means whereby the movement of the latch-bar in the central recess of the latch-frame operates said trigger, substantially as set forth.

4. A gate-latch comprising in combination, a latch-bar, a central recess in the latch-frame for receiving said bar, a pair of vertically-movable stop-bolts, locking-triggers for said stop-bolts, a pair of pivoted levers for raising said stop-bolts, and means whereby the movement of the latch-bar in the central recess of the latch-frame operates said trigger, substantially as set forth.

GEORGE WARNER.
